BOTTLE HOODING MACHINE

Robert M. Price, Springfield, Mass., assignor to
 Package Machinery Company, Springfield,
 Mass., a corporation of Massachusetts

Application February 7, 1936, Serial No. 62,823

8 Claims. (Cl. 226—80)

This invention relates to machines for securing hoods of flexible and preferably transparent material to the necks of milk bottles and the like by means of an adhesively coated tape wound circumferentially about the bottle neck. One object of the invention is to provide improved means for applying the tape around the neck of the bottle while the bottle is held stationary, in contrast to certain prior devices in which the bottle is rotated 10 while the tape applying device remains stationary. A further object is to provide an improved device for guiding and applying the tape to the hood. A further object is to provide improved devices of this character which will be applicable to either 15 a hand operated or an automatic machine. Additional objects will appear from the following description and claims.

Referring to the drawings.

Fig. 1 is a side elevation of a bottle holding 20 machine embodying the invention;

Fig. 2 is an enlarged top plan view of the tape applying apparatus;

Fig. 3 is an enlarged sectional view of the hooding and tape applying apparatus;

Fig. 4 is a perspective view of the tape applying finger;

Figs. 5, 6, and 7 are diagrammatic views showing progressive stages in the application of the tape to the hood; and

Fig. 8 is a detail of the hooded bottle.

The machine is supported on a plurality of vertical members 10 carrying legs 11. A table 12 is carried by the vertical members 10 just above the legs, and bears brackets 13 and 14. The bracket 35 13 serves as a bearing for a pair of spaced arms 15 and 16 having rearwardly extending projections 17 and 18 joined at their outer ends by a link 19. Fitted in the outer ends of the arms, and held as by a clamp screw 20, is a rod 21 bearing at its 40 upper end a support 22 for a milk bottle 23. A link 24 joins the lower arm 15 to a lever 25 pivoted on the bracket 14 and having a treadle extension 26 by the depression of which the milk bottle support may be raised to carry the bottle 45 into the zone of operation of the hooding and taping apparatus. If desired, a spring 27 joins the extension 18 to an upper table member 28 to assist gravity in returning the bottle support to its lowermost position, in which it is arrested by 50 contact of the extension 17 with a stop 29 formed on the bracket 13.

Supported by the upper table member 28 is a hooding device which forms no part of my present invention and which will therefore be described

only briefly. This hooding device comprises a guide 30 into which a sheet of hooding material may be introduced either manually or by some automatic device not here necessary to be shown, and a pleating apparatus which drapes the sheet of hood material downwardly around the neck of the bottle as the latter is elevated by the linkage described. The latter device comprises four segmental rubber members 31, each carried on a pivot 32, and divided at their inner peripheries 5 into fingers which drape and pleat the hood material about the bottle neck as the bottle is elevated through them and which hold it during the taping operation later to be described. When the hooded and taped bottle is again lowered, the segmental members rock on their pivots to permit the bottle to pass downwardly without danger of the rubber fingers disturbing the freshly applied tape.

The tape applying apparatus is rotatably mounted in a bearing 35 clamped as by a screw 36 20 in the end of a bracket 37 arising from the table 28. Rotatable within the bearing is a sleeve 38 prevented from moving upwardly within the bearing by an arm 39 pinned to the sleeve at 40, and from moving downwardly by a handle 41 pinned 25 to it at 42. Threaded through the sleeve 38, and held in adjusted position with respect to it by a lock nut 43, is a rod 44. The lower end of this rod is reduced in size as at 45, and bears upon this reduced portion a holder 46 having an interior 30 conical form so as to furnish a stabilizing support for the top of the bottle. The holder is secured to the rod as by a cotter pin 47, and is free to rotate relative to the rod; so that as the latter turns the holder may remain stationary upon the top of the 35 stationary bottle.

The arm 39 projects laterally so as to furnish support for a vertical shaft 50 upon which is fixed an upper finger 51 and a lower applicator finger 52. A pin 53 on the upper finger is joined by a 40 spring 54 to a lateral projection 55 of the arm 39, the spring being arranged substantially in line with the pivot shaft 50 so as to hold the two fingers either in an outer position shown in Fig. 2, in which the upper finger is held against further 45 outward motion by contact with a shoulder 56 on the arm 39, or in an inner position in which the applicator finger 52 rests against the bottle neck, with a yielding pressure. The applicator finger is shown in perspective in Fig. 4, and in its operation 50 in Figs. 5, 6 and 7. It is provided with a lateral notch 57 extending in a slanting direction and serving to receive a tape, and with a recess 58 opening out of the notch on that side near the end 55 of the finger and serving to guide the tape during

the application thereof to the hood. The end of the applicator finger is provided with a bearing surface 59 serving to press the tape against the hood.

5 The operation of the device will now be described. A bottle 23 is placed upon the support and a sheet of hood material *h* introduced either by hand or by a suitable automatic feed upon the guide 30. Upon depression of the treadle 26 the 10 bottle will be elevated, picking the hood material off from the guide 30 and carrying it upwardly through the circular series of rubber fingers. This drapes the hood over the bottle top in somewhat the condition shown in Fig. 3, and clamps 15 the hood between the bottle top and the holder 46. A length of tape *t* is now taken from any suitable source, its surface coated with adhesive or with a solvent for whatever adhesive coating there may be on it, in case the tape is not naturally adhesive, and one end placed within the slot 51 so as to enter the recess 58. The applicator finger is then moved so as to contact with the tape and carry it into firm contact with the hood 20 on the bottle as in Fig. 6, preferably by pushing 25 on the end of the upper finger 51 with the hand. The applicator finger may now be carried around the bottle by rotating the sleeve 38 by means of the handle 41. In this rotation the tape remains 30 within the recess 58, and is guided by it into accurate registration with the hood around the periphery of the bottle neck. This part of the operation is indicated in Fig. 6. The tape is preferably chosen of such a length as to overlap upon itself 35 as in Fig. 7, and when its full length has been applied to the hood the applicator finger is once more removed from contact with the bottle by an outward pressure upon the upper finger 51. Pressure on the treadle 26 is then removed, and the bottle sinks through the rubber fingers which 40 rotate as described above, to permit the bottle to move freely without danger of stripping the freshly applied hood.

What I claim is:

1. In a bottle hooding machine having means 45 for draping a hood over the mouth and neck of a bottle, a guide rotatable about the bottle for guiding a length of adhesive tape into contact with a hood so draped over the bottle, and a device rotating around the bottle for pressing the 50 tape so guided directly against the hood and into adherent contact therewith throughout its circumference.

2. In a bottle hooding machine having means 55 for draping a hood over the mouth and neck of a bottle and holding the hood adjacent the bottom portion of the skirt thereof, a guide rotatable about the bottle in a plane above that portion of the hood which is being held, said guide being adapted to guide a length of adhesive tape into 60 contact with a hood so draped over the bottle, and a device rotatable around the bottle for pressing the tape so guided directly against the hood and into adherent contact therewith throughout its circumference.

3. In a bottle hooding machine having means for draping a hood over the mouth and neck of a bottle and holding the hood adjacent the bottom portion of the skirt thereof, means for clamping the central portion of the hood to the top 5 of the bottle, a guide rotatable around the bottle in a plane between the two portions of the hood so held to the bottle, said guide being adapted to guide a length of adhesive tape into contact with a hood so draped over the bottle, and a 10 device rotatable around the bottle for pressing the tape so guided directly against the hood and into adherent contact therewith throughout its circumference.

4. In a machine for securing a hood upon a 15 bottle, means for supporting a bottle against rotation, a member rotating about the axis of the bottle, an applicator finger mounted upon said member, means for holding said finger either in contact or out of contact with the bottle neck, 20 and means carried by said finger for guiding and pressing an adhesive tape into adherent contact with a hood on the bottle.

5. In a machine for securing a hood upon a 25 bottle, means for supporting a bottle against rotation, a member rotating about the axis of the bottle, an applicator finger mounted upon said member and having a surface positioned to press a tape into adhering contact with a hood on the 30 bottle and with a guide directing the tape into registry with said hood around its circumference, and means for holding said applicator finger either in yielding contact with or out of contact with the hood on the bottle.

6. In a machine for securing a hood upon a 35 bottle, an applicator finger, means for moving said finger either into yielding contact with a hood on the bottle or into a position out of contact with the bottle, and means for rotating the finger around the neck of the bottle. 40

7. In a machine for securing a hood upon a bottle, an applicator finger having a tape receiving slot therein and a hood contacting surface adapted to press against a hood on the bottle the tape so guided, means for moving said finger 45 either into yielding contact with a hood on the bottle or into a position out of contact with the bottle, and means for rotating the finger around the neck of the bottle.

8. In a machine for securing a hood upon a 50 bottle, an applicator finger having a tape receiving slot therein and a hood contacting surface adapted to press the tape so guided into adhering contact with the hood on the bottle, the slot having a laterally offset recess opening out of it into 55 which the tape may be received to preserve its alignment with respect to the contacting surface of the finger, means for moving said finger either into yielding contact with a hood on the bottle or into a position out of contact with the bottle, 60 and means for rotating the finger around the neck of the bottle.

ROBERT M. PRICE.
